UNITED STATES PATENT OFFICE.

MAX PRÜSS, OF ESSEN, GERMANY.

DISCHARGING DEVICE FOR SLUDGE BASINS.

Application filed October 26, 1922. Serial No. 597,213.

To all whom it may concern:

Be it known that I, MAX PRÜSS, a citizen of the German Republic, and residing at Essen, Germany, have invented certain new and useful Improvements in a Discharging Device for Sludge Basins, of which the following is a specification.

The present invention relates to improvements in discharging devices for sludge basins, and it has for its object to overcome the drawbacks prevalent in existing devices used in this capacity, by providing an improved arrangement, which is represented, by way of example, on the accompanying drawing, 15 in which:

Fig. 1 is a cross section through a sewage basin with sludge settled therein,

Fig. 2 is a front view of a suction shovel hereinafter described and by means of which 20 the sludge below water level is to be digged off,

Fig. 3 is a longitudinal section through said ladle with a suction orifice and a rinsing pipe hereinafter described,

Fig. 4 is a cross section through a narrow sewage basin with a bridge construction running over the same and on which said shovel and a plow hereinafter described are adjustable in their position of height,

Fig. 5 is a longitudinal section through the middle of the sewage basin shown in Fig. 4.

According to the invention, the sludge is not compelled to flow to the suction orifices or to be driven toward the latter by the 35 water sucked off with the sludge, as is the case with sludge pumps having stationary pipes, but the suction orifice is continuously pressed against the sludge settled in the basin. For this purpose, the suction orifice 40 *a* (Fig. 1) is longitudinally movable on a bridge construction *b* with a truck *h* and adjustable on said track in its position of height. With rectangular basins, the bridge *b* is made to run to and fro over the basin, while with 45 round basins, it moves circularly over the water level. Thus, by a movement of the bridge, by a displacement of the suction orifice along the bridge, and by the adjustment of its position of height on the bridge, e. g.

50 by a movement to 3 coordinates, the suction orifice can be brought to any place of the basin to be emptied. The sludge is thus digged off automatically in layers and strips from its position below water level. In order to permit said digging off without stirring up the sludge, e. g. without disturbing

the clearing work not to be interrupted, the suction orifice is fitted with a digging shovel *c* similar to the dredging ladle of a bag scoop (Figs. 2 and 3). Said shovel may also be closed at the top *d*. The sludge digged off in broad strips is forced into the shovel when advancing the latter and sucked off from the shovel from up above without any danger of water breaking through. In Fig. 1, the suction orifice is attached, by means of a flexible pipe *f*, to the stationary suction pipe *g* leading to the pump. In some cases, it may be preferable to locate the pump on the truck *h*, which is movable on the bridge *b* for a 60 displacement of the suction shovel, and to 65 make the pressure pipe flexible.

By an advance of the suction shovel the sludge with the water contents is forced into the shovel in the condition as it has settled 75 in the sludge basin. Coarse-grained sludge is there frequently so compact that it is not capable of being pumped. In such cases, it is necessary to stir up the sludge in front of the suction orifice *a* or even to add some 80 water thereto in order to make it capable of being pumped. For this purpose, a rinsing pipe *e* with spraying nozzles is provided in the shovel, through which compressed air or water is forced into the sludge in the shovel 85 or mixing water is sucked therein from the water above the sludge by the suction effect within the shovel.

In this connection, it is also possible to add to the pressure water chemical substances required for a further treatment of the sludge and the mixing of which with the sludge on its way through the pipings and the pump is as intimate as possible. Thus, for instance, lime-milk may be added, 90 through the rinsing pipe during the pumping off, to sludge capable of putrefaction, 95 which, though harmless in water, would cause bad smells in the atmosphere.

By the addition of rinsing water to the 100 sludge, the latter can be delivered of such a consistency as is desired for its further treatment.

By the adjustability of the suction shovel, in its position of height, the whole discharging device can be put above water level in its position of rest (see dotted position Fig. 1), and here cleaned and preserved. Not one single pipe, no slide, no movable part remains then below water. With large 105 clearing plants suffices the provision of the discharging device for one basin only, the 110

whole device being so designed that it can be run, together with the whole suction pipes required and the pump house, from one basin to the others and need be attached 5 to the pressure pipe of each basin only.

The constructional details of the bridges and their moving contrivances may be of any appropriate type. Circularly moving bridges may run on the circumferential 10 wall of the basin, or on the basin circumference and a central pillar, or as a portable turning-crane on the latter only, which may be connected with the pillar of the adjacent basin by a track for the turning-crane. The 15 movability of the bridge must always be such that the suction ladle can be led to any place of the sludge basin.

The displacement of the suction ladle along the bridge requires a certain expenditure of construction, which can be reduced 20 by arranging, instead of one shovel only, a plurality of same which are adjustable in their position of height on the bridge and which can be lowered successively and put 25 to work. Thereby, the stripwise digging off of the sludge is attained in the same way. Said shovels may be arranged directly beside each other, though the working extent of each shovel in lateral directions may 30 be increased by shifting the sludge onto the respective shovel by means of a plow *i*, which is adjustable in its position of height on the bridge (Figs. 4 and 5). A whirling up of the sludge need not be feared owing to the 35 speed of advance amounting to some millimeters per second only. The plows, can, of course, also be employed in connection with circularly moving bridges.

What I claim, is:—

40 1. In a discharging device for sludge basins, the combination of a bridge movable over the basin, and a suction shovel movable along and adjustable in its position of height on said bridge, substantially as set forth.

45 2. In a discharging device for sludge basins, the combination of a bridge movable over the basin, a suction shovel movable along and adjustable in its position of 50 height on said bridge, and a rinsing pipe

with spraying nozzles in said shovel designed to dilute therethrough the sludge in the shovel by supplying a pressure medium thereto, substantially as set forth.

3. In a discharging device for sludge basins, the combination of a bridge movable over the basin, a suction shovel movable along and adjustable in its position of height on said bridge, and a rinsing pipe 55 with spraying nozzles in said shovel designed to dilute therethrough the sludge in the shovel by sucking mixing water therein from the water above the sludge by the suction effect within the shovel, substantially as set forth.

4. In a discharging device for sludge basins, the combination of a bridge movable over the basin, a suction shovel movable along and adjustable in its position of height on said bridge, and a rinsing pipe 60 with spraying nozzles in said shovel designed to dilute therethrough the sludge in the shovel by supplying a pressure medium thereto and at the same time to mix therethrough the sludge with chemical substances, substantially as set forth.

5. In a discharging device for sludge basins, the combination of a bridge movable over the basin, and a plurality of suction shovels adjustable in their position of height on said bridge and adapted to be successively lowered and put to work, substantially as set forth.

6. In a discharging device for sludge basins, the combination of a bridge movable over the basin, a suction shovel movable along and adjustable in its position of height on said bridge, and a plow adjustable in its position of height on said bridge and designed to increase the working extent of 70 said shovel in lateral directions, substantially as set forth.

In testimony whereof I have hereunto set my hand in the presence of two subscribing witnesses.

MAX PRÜSS.
